Des. 191,072
Patented Aug. 8, 1961

191,072

COMBINATION PITCHER AND JAR

Clara Virginia Eicholtz, Midland, Mich., assignor to The Dow Chemical Company, Midland, Mich., a corporation of Delaware

Filed Dec. 29, 1960, Ser. No. 63,387

Term of patent 14 years

(Cl. D58—25)

FIGURE 1 is an elevational view of a combination pitcher and jar showing my design;

FIGURE 2 is a top plan view thereof; and

FIGURE 3 is a perspective view thereof.

The side not shown of the present combination pitcher and jar is the same as the side shown.

I claim:

The ornamental design for a combination pitcher and jar, as shown and described.
